UNITED STATES PATENT OFFICE.

WILLIAM H. GOLDSBERRY, OF CHICAGO, ILLINOIS.

DESIGN FOR A MEASURING-RULE.

SPECIFICATION forming part of Design No. 22,124, dated January 10, 1893.

Application filed September 8, 1892. Serial No. 445,372. Term of patent 14 years.

To all whom it may concern:

Be it known that I, WILLIAM H. GOLDSBERRY, a citizen of the United States, residing at Chicago, in the county of Cook and 5 State of Illinois, have invented and produced a new and original Design for Measuring-Rules, of which the following is a specification, reference being had to the accompanying drawings, showing a part thereof.

o The leading feature of my design consists in a measuring rule as herein shown provided with a series of lines transverse to the length thereof and with a second series of lines diagonal to the said transverse lines.

5 In the accompanying drawings, Figure 1 is a plan view, and Fig. 2 is an edge view.

A, A, are the unit spaces extending transversely across the rule. These spaces are separated by lines, B.

o C, C, are lines extending substantially par-

allel to the length of the rule across the unit spaces. In the drawings, the lines, C, are shown straight and extend obliquely from the lower portion of one side of each unit space upward to the upper portion of the other side 25 of the same unit space. Thus the end of the lines, C, are made non-coincident, and each such line is made individually conspicuous, and the design as a whole is given a peculiar irregularity.

30 What I claim is—

The design for a rule, substantially as herein shown and described.

In testimony whereof I affix my signature, in presence of two witnesses, this 31st day of Au- 35 gust, 1892.

WILLIAM H. GOLDSBERRY.

Witnesses:

AMBROSE RISDON,

CYRUS KEHR.
